PATENTED MAR. 3, 1908.

H. G. GILLMOR.
MEANS OF FORMING JOINTS IN ELECTRICAL CONDUCTORS.

APPLICATION FILED FEB. 4, 1907.

UNITED STATES PATENT OFFICE.

HORATIO G. GILLMOR, OF BATH, MAINE.

MEANS OF FORMING JOINTS IN ELECTRICAL CONDUCTORS.

No. 880,789.

Specification of Letters Patent.

Patented March 3, 1908.

Application filed February 4, 1907. Serial No. 355,598.

To all whom it may concern:

Be it known that I, HORATIO G. GILLMOR, a citizen of the United States, residing at Bath, in the county of Sagadahoc, State of Maine, have invented an Improvement in the Means of Forming Joints in Electrical Conductors, of which the following is a specification accompanied by drawings.

My invention relates to joints in electrical conductors and has particular reference to joints in rails employed as electrical conductors although the means employed are not limited to joints in such rails but may be used in any connection in which they may be found applicable.

One object of my invention is to provide at the joints in electrical conductors a conductivity as nearly as possible equal to the conductivity of the unjoined portions of such conductors.

Another object of the invention is to so construct such joints that the conductors may be free to the changes in length incident to changes in temperature without effect upon the conductivity of the joint.

Further objects of the invention will hereinafter appear and to these ends the invention consists of a joint for carrying out the above objects, embodying the features of construction, combination of elements and arrangement of parts having the general mode of operation substantially as hereinafter described and claimed in this specification and shown in the accompanying drawings in

which:

Figure 1 is a side elevation illustrating a form of the joint. Fig. 2 is a vertical section through the parts at the plane indicated by V V in Fig. 1. Figs. 3 and 4 are, respectively, a vertical section through the parts and a horizontal section at the plane Z Z, looking down, of the joint applied to conductors of another form. Fig. 5 is a perspective view of the self-locking wedge employed.

Similar letters refer to similar parts throughout the several views.

A A are the conductors to be joined.

B B are bars or plates overlapping the conductors at their sides.

C C is a clamp body or chair.

D D are locking wedges having double wedging surfaces and are arranged to interlock at E with the chair or clamp body C when the wedges are driven to their final position, so as to prevent movement of the wedge D in relation to the chair or clamp C,

and having stops F which will come into contact with the end of the chair or clamp body C when the wedge is driven to prevent the wedge from being driven too far.

60

G G are pins or rods traversing the bars or plates B and one of the conductors.

H H are spikes or screws used for securing the conductors to their supports T.

K K are bars or plates overlapping the bottoms of the conductors, extending for some distance beyond the ends of the clamp body or chair and arranged to interlock with the clamp body or chair as shown.

65

The surfaces or contact I I of the bars or the plates B and K and the wedges D with the conductors are provided with a solid adherent coating of a metal such as zinc, tin, etc.; which, while possessing relatively high electrical conductivity, also withstand the corrosive action of the elements.

70

To make up the joint the conductors to be joined are placed in line on the bar or plate K and the bars or plates B placed at each side. The pins G, traversing the bars and one conductor, are placed, to prevent longitudinal movement of the parts with respect to one conductor. The clamp body or chair is then placed in position and the wedges D driven between the arms of the clamp body or chair and the other parts of the joint. The wedges are preferably formed with double wedging surfaces; and, through the action of one set of the wedging surfaces, lateral pressure is brought to bear upon the parts of the joint; while the wedging action of the other wedging surfaces

80

exerts vertical pressure upon the parts of the joint. The elasticity of the clamp arms is sufficient to allow the arm of the clamp to spring as the wedge is being driven to permit the interlocking surfaces of the clamp and wedge to pass one another and the interlocking of the clamp and wedge is effected automatically by the elasticity of the clamp causing the clamp arm to spring back and so interlock the surfaces of the wedge and clamp arm at E.

90

The bars overlapping the meeting conductors have surfaces in contact with the conductors, the aggregate area of which is several times that of a right section of either conductor. The pressure exerted by the wedges upon the parts of the joint bring these surfaces into intimate contact with the conductors. The metallic coatings upon the surfaces of parts in contact with the conductors insure good conditions as to conductivity at all points of contact of the joint

parts with the conductors. The surfaces of those portions of the ends of the conductors coming in contact with the parts of the joint should be freed as far as possible from oxid, 5 scale, etc., so that when the joint is made up good metallic surfaces will be presented for contact. Even though, however, the surfaces of contact of the conductors with the parts of the joint are not entirely free from 10 oxid, etc., the large area of the surfaces of contact of the conductors with the parts of the joint and the pressure exerted to bring into intimate contact the conductors and the parts going to make up the joint will insure 15 low electrical resistance at the joint; and it is found that, when rails are employed as electrical conductors, the use of a metallic coating applied to the contact surfaces of the bars and other parts of the joint necessary to 20 provide adequate mechanical strength as above described makes the strength member of the joint in conjunction with this metallic coating, a bond; and provides for ample conductivity at the joint.

25 In coating the parts of the joint it will often be convenient to cover all of the exterior surfaces of some of the parts instead of coating only those surfaces which come in contact with the conductors. The pins traversing 30 one conductor and parts of the joint and the interlocking of the wedges and the clamp effectually secure the parts of the joint against longitudinal movement with respect to this one conductor. The other conductor 35 is held by the parts of the joint through the clamping action exerted upon them, and longitudinal changes of position of this conductor with respect to the parts of the joint are resisted only by the friction of the surfaces of contact. This conductor is therefore free to the slight changes in length occasioned by changes in temperature while the 40 area of the surfaces of contact and hence the electrical conductivity through these surfaces remains practically constant. The joint constructed in the manner described provides for the changes in relative positions of the parts incident to varying temperature 45 without detrimental effect upon the conductivity at the joint.

Obviously this invention may be embodied in widely varying forms, therefore,

Without limiting the invention to the construction shown and described, nor enumerating equivalents, I claim and desire to secure by Letters Patent the following:

1. The combination of electrical conductors and a joint for the adjacent ends thereof, including, a chair having upwardly extending arms, and a wedge constructed with two wedging surfaces whereby pressure is exerted both transversely and vertically upon the parts of the joint, substantially as described.

2. The combination of electrical conductors and a joint for the adjacent ends thereof,

including, a part composed partly of rust-proof material over-lapping the meeting ends of the conductors, a chair having upwardly extending arms and a wedge constructed with double wedging surfaces whereby pressure is exerted in two directions approximately at right angles upon the parts of the joint, substantially as described.

3. The combination of electrical conductors and a joint for the adjacent ends thereof, including, a part composed partly of corrosion-proof material over-lapping the meeting ends of the conductors, a chair having upwardly extending arms, a wedge constructed with two wedging surfaces whereby pressure is exerted upwardly and inwardly upon the parts of the joint, and fastening means whereby the joint is secured against movement with respect to one of the said conductors, substantially as described.

4. The combination of electrical conductors and a joint for the adjacent ends thereof, including a chair having upwardly-extending arms, a bar between said chair and said conductors, and a wedge having two wedging surfaces, whereby an inward and upward pressure is exerted upon the parts of the joint, substantially as described.

5. The combination of electrical conductors and a joint for the adjacent ends thereof, including a chair having upwardly extending arms, a bar composed in part of rust-proof material between said chair and said conductors, and a wedge having two wedging surfaces, whereby an inward and upward pressure is exerted upon the parts of the joint, substantially as described.

6. The combination of electrical conductors and a joint for the adjacent ends thereof, including a chair having upwardly-extending arms, bars overlapping the ends of said conductors, and wedges between the arms of the chair and said bars substantially as described.

7. The combination of electrical conductors and a joint for the adjacent ends thereof, including a chair having upwardly-extending arms, bars composed partly of rust-proof material overlapping the ends of said conductors, and wedges between the arms of the chair and said bars, substantially as described.

8. The combination of electrical conductors and a joint for the adjacent ends thereof, including a chair having upwardly-extending arms, bars overlapping the ends of said conductors, wedges between said arms and bars, and fastening means to hold the joint in place, substantially as described.

9. The combination of electrical conductors and a joint for the adjacent ends thereof, including bars composed partly of rust-proof material, a chair having upwardly-extending arms, wedges between said arms and bars, and fastening means to hold the joint in place, substantially as described.

10. The combination of electrical con-

ductors, and a joint for the adjacent ends thereof, including a chair having upwardly extending arms, plates overlapping the ends of said conductors, and wedges between a 5 plate and an arm of said chair at opposite sides of the conductors, substantially as described.

11. The combination of electrical conductors, and a joint for the adjacent ends thereof, including a chair having upwardly extending arms, plates composed partly of 10 rust-proof material overlapping the ends of said conductors, and wedges at opposite sides of the conductors between an arm of 15 the chair and a plate, substantially as described.

12. The combination of electrical conductors and a joint for the adjacent ends thereof, including a chair having upwardly 20 extending arms, bars between the said chair and said conductors, a wedge driven in between an arm of the said chair and one of 25 said bars, and fastening means to hold the joint in place, substantially as described.

13. A joint for electrical conductors including, in combination with the conductor bars composed partly of rust-proof material, a chair having upwardly extending arms, a wedge between an arm of the chair and one 30 of said bars, and fastening means whereby 35 the joint is secured against movement with respect to one of the said conductors, substantially as described.

14. The combination of electrical conductors and a joint for the adjacent ends thereof, including a chair having upwardly 40 extending arms overturned inwardly at their upper edges, plates overlapping the ends of said conductors, and wedges having two wedging surfaces whereby an upward pressure is exerted upon one of said plates and an

inward pressure upon plates at opposite sides of said conductors, substantially as described.

15. The combination of electrical conductors and a joint for the adjacent ends 45 thereof, including a chair having upwardly extending arms overturned inwardly at their upper edges, plates composed partly of corrosion-proof material overlapping said conductors and wedges having two wedging surfaces, whereby an upward pressure is exerted 50 upon one of said plates and an inward pressure exerted upon plates at opposite sides of said conductors, substantially as described.

16. The combination of electrical conductors and a joint for the adjacent ends 55 thereof, including a chair having upwardly extending arms, bars between said arms and said conductors, a plate between said chair and said conductors, wedges between said 60 arms and said bars, and fastening means to hold the joint in place, substantially as described.

17. The combination of electrical conductors and a joint for the adjacent ends 65 thereof, including a chair having upwardly extending arms, bars, composed partly of rust-proof material, between said arms and said conductors, a plate between said chair and said conductors, wedges between said 70 arms and said bars, said chairs, bars, plate and wedges overlapping the adjacent ends of said conductors, and pins passing through said bars and one of said conductors, substantially as described. 75

In testimony whereof I have signed these specifications in the presence of two subscribing witnesses.

H. G. GILLMOR.
